DESIGN FOR A GASOLINE HOIST

Charles F. Peterson, Arlington, Mass., assignor
to New England Trawler Equipment Co.,
Chelsea, Mass., a corporation of Massachusetts

Application April 1, 1946, Serial No. 128,134

Term of patent 14 years

(Cl. D41—1)

To all whom it may concern:

Be it known that I, Charles F. Peterson, a citizen of the United States, residing at Arlington, in the county of Middlesex and Commonwealth of Massachusetts, have invented a new, original, and ornamental Design for a Gasoline Hoist, of which the following is a specification, reference being had to the accompanying drawing, forming a part thereof, in which:

The figure is a view in perspective of a gasoline hoist, showing my new design. The side of the hoist not shown in the figure is substantially plain.

I claim:

The ornamental design for a gasoline hoist, substantially as shown and described.

CHARLES F. PETERSON.
